(57) **CLAIM**

The ornamental design for a display screen or portion thereof with graphical user interface, as shown and described.

DESCRIPTION

The patent or application file contains at least one drawing executed in color. Copies of this patent or patent application

publication with color drawing(s) will be provided by the Office upon request and payment of the necessary fee.

FIG. 1 is a front view of a first embodiment of a display screen or portion thereof with graphical user interface showing the new design;

FIG. 2 is a front view of a second embodiment of a display screen or portion thereof with graphical user interface showing the new design;

FIG. 3 is a front view of a third embodiment of a display screen or portion thereof with graphical user interface showing the new design;

FIG. 4 is a front view of a fourth embodiment of a display screen or portion thereof with graphical user interface showing the new design;

FIG. 5 is a front view of a fifth embodiment of a display screen or portion thereof with graphical user interface showing the new design;

FIG. 6 is a front view of a sixth embodiment of a display screen or portion thereof with graphical user interface showing the new design;

FIG. 7 is a front view of a seventh embodiment of a display screen or portion thereof with graphical user interface showing the new design;

FIG. 8 is a front view of an eighth embodiment of a display screen or portion thereof with graphical user interface showing the new design;

FIG. 9 is a front view of a ninth embodiment of a display screen or portion thereof with graphical user interface showing the new design;

FIG. 10 is a front view of a tenth embodiment of a display screen or portion thereof with graphical user interface showing the new design;

FIG. 11 is a front view of an eleventh embodiment of a display screen or portion thereof with graphical user interface showing the new design; and,

FIG. 12 is a front view of a twelfth embodiment of a display screen or portion thereof with graphical user interface showing the new design.

The outermost even-length broken lines illustrate portions of a display screen and form no part of the claimed design. The remaining broken lines illustrate portions of the graphical user interface and form no part of the claimed design.
